UNITED STATES PATENT OFFICE.

ERNEST FUCHS, OF GUADALAJARA, MEXICO.

WATCH-CHARM.

992,648.

Specification of Letters Patent. Patented May 16, 1911.

Application filed August 5, 1910. Serial No. 575,697.

To all whom it may concern:

Be it known that I, ERNEST FUCHS, a citizen of the Republic of the United States of America, residing at Guadalajara, in the 5 State of Jalisco and Republic of Mexico, have invented new and useful Improvements in Watch-Charms, of which the following is a specification.

This invention relates to improvements in 10 watch charms, and the primary object of the invention is to provide a watch charm comprising an ornamental body portion having its lower end formed with a seal and an inner portion, which is readily removable 15 from the outer or body portion provided with a small scale adapted for weighing letters, coins or other light articles.

With the above, and other objects in view, which will appear as the description progresses, the invention resides in the novel construction and combination of parts hereinafter fully described and claimed.

In the accompanying drawings there has been illustrated a simple and preferred embodiment of the improvement, and in which drawings,

Figure 1 is a front elevation of a watch charm constructed in accordance with the present invention. Fig. 2 is a front elevation of the inner or scale member removed from the outer shell. Fig. 3 is a side elevation of the same. Fig. 4 is a vertical longitudinal sectional view of the same. Fig. 5 is a vertical transverse sectional view of Fig. 35 1. Fig. 6 is an enlarged detail sectional view illustrating the spring compensating device. Fig. 7 is a bottom plan view of Fig. 1.

The improved charm comprises essentially 40 an outer member or casing 2 and an inner member or scale 3. The outer member 3 is preferably circular in cross section, and may be of any desired ornamental design. The lower end of the outer member or casing 2 is 45 provided with a seal 4 upon which the initials of the owner may be designed and the same employed for stamping letters or making an impression upon the seal of a letter. The upper end of the member 2 is 50 open and its inner wall is provided with threads 5 which extend a suitable distance and which are adapted to engage with similar threads 6 provided upon the upper circular portion of the member 3. The member 55 3 is adapted to project a slight distance

above the top of the member 1 and this projecting portion is provided with suitable eye 7 whereby the catch of a watch chain may be connected with the charm. The body of the member 3 below its threaded portion 6 is provided with a flattened face 8, the same having a central vertical slit or opening 9 through which is adapted to project the indicating hands. The flattened face 8 is provided with suitable graduations positioned adjacent the ends of the flattened face 8, and the indicator 10 is preferably provided with two hands to contact with the graduations upon both of the edges of the face 8. The indicator 10 is connected with 60 a tubular member 11 which is adapted to slide upon a depending rod 12 carried by the member 6. The tubular member 11 is constructed of some suitable resilient material and has its lower extremity slotted so as to 65 provide a pair of engaging jaws 13. These jaws 13 have one of their faces substantially flattened as illustrated in Figs. 2 and 5 of the drawings so that the same is readily grasped obtaining a bearing upon the article 70 to be weighed.

The numeral 14 designates a helical spring which bears against the offset portion of the tube provided by the indicator arm 10, and the lower extremity of this spring is 85 mounted within the threaded bushing 15 which is rotatably connected with a threaded opening provided within the lower portion of the member 3.

From the above description, taken in connection with the accompanying drawings, it will be noted that I have provided an extremely simple and effective device for the purpose intended, and while I have illustrated and described the preferred embodiment of the improvement, as it now appears to me, minor details of construction, within the scope of the following claim may be resorted to if desired.

Having thus fully described the invention, 90 what I claim as new is:—

A watch charm comprising an ornamental cylinder having one of its ends open and its opposite end closed to form a seal, a removable member for the casing, said member 105 being provided with a flattened face having a central vertical opening, an indicator arm projecting through said opening, a cylinder connected with the arm, said cylinder being constructed of resilient material and having 110

its lower ends slitted to provide engaging fingers, a depending rod for the cylinder, a helical spring surrounding the cylinder and contacting the offset indicating arm, the opposite end convolution of the cylinder being provided with an adjustable bushing, substantially as and for the purpose set forth.

In testimony whereof I affix my signature in presence of two witnesses.

ERNEST FUCHS.
